SHOE LATCH

Ralph E. Jones, San Diego, Calif., assignor of one-half to Kelso Jones, San Diego, Calif.

Application July 2, 1948, Serial No. 36,678

6 Claims. (Cl. 24—71)

1

My invention relates to a shoe latch, more particularly for tightening the upper portions of shoes upon the feet of a person, and for fastening the same securely against loosening. This application is a continuation-in-part of my co-pending application, Serial No. 762,326, filed July 21, 1947, now abandoned, and the objects of my invention are:

First, to provide a shoe latch of this class whereby the upper parts of the shoe may be instantly drawn toward each other to a predetermined degree and reliably fastened there, all in one quick movement, without conscious thought, skill or appreciable effort, thus saving much time in comparison to the old shoe lace arrangement, which requires particular attention to the tension adjustment each time a shoe is placed upon the foot, and thus eliminating completely the otherwise notoriously troublesome shoe lace;

Second, to provide such a shoe latch that the fastening means may be unfastened and the upper shoe parts liberally loosened and separated with no less speed, ease and efficiency, this likewise with but a single movement;

Third, to provide such a shoe latch so arranged that the fitting—the tension of the upper across the foot—may be easily, quickly, satisfactorily and reliably adjusted, initially or when desired, without the need of any tool except a coin such as a penny or a quarter, and so arranged that the shoe may normally be repeatedly put on and taken off day after day without any need for bothering with or changing such tension adjustment;

Fourth, to provide such a shoe latch as will present a simple, neat and attractive exterior appearance, with all metal parts concealed beneath the necessary leather parts, and with no obstructions, either unsightly or such as to interfere with quick and satisfactory polishing;

Fifth, to provide such a shoe latch that the fitting or tension adjustment is made by moving all metal parts as a unit relative to the leather upper upon which mounted, and without any disturbance of the connection of the tension strap to the lever; and

Sixth, to provide such a shoe latch which is conducive to comfort, economical in construction, efficient, reliable and satisfactory in operation, and which will not readily deteriorate or get out of order.

With these and other objects in view, as will appear hereinafter, my invention consists of certain novel features of construction, combination and arrangement of parts and portions, and certain modifications, as will be hereinafter described in detail and particularly set forth in the appended claims, reference being had to the accompanying drawings and to the characters of reference thereon, forming a part of this application, in which:

Fig. 1 of the drawing is a perspective view of

2

my shoe latch, shown in closed position and in connection with a shoe; Fig. 2 is a side elevational view of my shoe latch, shown in open position and showing a shoe fragmentarily in connection therewith; Fig. 3 is a side elevational view of a shoe shown fragmentarily and illustrating my shoe latch in connection therewith; Fig. 4 is an enlarged fragmentary sectional view taken from the line 4—4 of Fig. 2; Fig. 5 is an enlarged fragmentary sectional view taken from the line 5—5 of Fig. 2, showing a part in varied position by dash lines; Fig. 6 is a fragmentary side elevational view of one of the shoe uppers slotted to receive the anchor stud of my shoe latch; Fig. 7 is a side elevational view of the nut of my shoe latch; Fig. 8 is a sectional view taken from the line 8—8 of Fig. 7; Fig. 9 is a sectional view taken from the line 9—9 of Fig. 7; Fig. 10 is a side elevational view of a modified form of nut used in connection with my shoe latch; Fig. 11 is a sectional view taken from the line 11—11 of Fig. 10; Fig. 12 is a sectional view taken from the line 12—12 of Fig. 10; Fig. 13 is another modified form of nut used in connection with my shoe latch; Fig. 14 is a sectional view taken from the line 14—14 of Fig. 13; and Fig. 15 is a sectional view taken from the line 15—15 of Fig. 13.

Similar characters of reference refer to similar parts and portions throughout the several views of the drawing.

The tension member 1, pivot mounting element 2, lever 3, stud 4, nut 5 and the shoe uppers 6 and 7 constitute the principal parts and portions of my shoe latch, the pivot mounting element 2 and the lever 3 comprising first and second securing members of the invention.

As shown in Fig. 1 of the drawings, my shoe latch, when installed in connection with a shoe, is entirely covered by one of the shoe elements, the tension member 1. In the closed position, as shown in Fig. 1 of the drawings, the tension member 1 completely obscures the operating mechanism of the shoe latch and presents a very neat, compact appearance. Pivotal connected to the outswinging end 1a of this tension member 1 is the lever 3, which is a substantially U-shaped member having inwardly directed opposed end portions 3a and 3b, which extend through openings in opposite side walls or rails of the pivot mounting element 2, shown best in Fig. 5 of the drawings, which is preferably made of stainless steel sheet metal, or the like. This pivot mounting element 2 is substantially U-shaped in cross-section to provide the aforesaid rails, as shown in Fig. 5 of the drawings, and is provided with outwardly extending, slightly inclined flange portions or edges 2a and 2b, which converge slightly toward the pivotal connections of the ends 3a and 3b of the lever 3, therewith, as shown best in Fig. 2 of the drawings. The tension member 1 is preferably of leather, or other material similar to that of which the shoe

is constructed, and is connected to the shoe upper 7 by sewing, or otherwise, as desired, while the pivot mounting element 2 is adjustably connected to the shoe upper 6 by means of the stud 4 engaged by the nut 5, as shown in Fig. 4 of the drawings, wherein the stud 4 extends through a slot 6a in the shoe upper 6, permitting adjustment of the stud 4 in said slot 6a transversely of the arch of the shoe in order to accommodate different proportions of different feet which may be positioned within the shoe. The stud 4 is provided with an enlarged diameter relatively thin head portion 4a, having a convex outer surface 4b, and an annular bearing portion 4c which is relieved concentrically of the screw-threaded portion 4d of the stud 4, greatly increasing the frictional retention at the engaging side of the head portion 4a of the stud 4, effectively preventing accidental rotation and loosening thereof. As shown in Fig. 4 of the drawings, the threaded shank 4d of the stud 4 extends through an opening 2c in the web 2d of the U-shaped in cross-section pivot mounting element 2, and the nut 5, externally screw-threaded on the screw-threaded shank 4d of the stud 4, is jammed against the outer side of the web 2d, as shown in Figs. 4 and 5 of the drawings, for compressively engaging the head 4a of the stud 4 with the inner side of the shoe upper 6, overlapping the slotted portion 6a therein. The nut 5, as shown best in Figs. 2 and 4 of the drawings, is provided with a chordally disposed slotted portion 5a positioned outwardly of the periphery of the screw-threaded shank 4d of the stud 4. This slot 5a, shown best in Fig. 8 of the drawings, is arcuate longitudinally thereof, as shown in section, and arranged to receive the peripheral edge of a coin, or the like, for tightening the nut against the inner web 2d of said pivot mounting element 2. It will be noted that the nut 5 is provided with a large diameter annular frictional bearing 5b, similar to the bearing 4c of the head 4a of the stud 4, causing efficient frictional engagement of the nut 5 with the web 2d of the pivot mounting element 2. The ends of the slot 5a are relatively shallow, which greatly strengthens the periphery of the nut 5 at each opposite terminus of the slot 5a, all as shown best in Figs. 7, 8 and 9.

The operation of my shoe latch is substantially as follows: When the latch is in the closed position as shown in Fig. 1 of the drawings, and it is desired to release the same for spreading the uppers 6 and 7 of the shoe in order to remove a person's foot from the shoe, the end 1a of the tension member 1 is raised upwardly from the upper 6 of the shoe, causing pivotal movement of the lever 3 at its opposite ends, into the position as shown in Fig. 2 of the drawings, whereby the uppers 6 and 7 of the shoe are released in one single motion. It will be noted that during the raising motion of the lever 3, that opposite side members 3c and 3d thereof spread apart, widening the distance between the ends 3a and 3b, due to the spreading action of the U-shaped lever 3, caused by passage thereof over the outer edges 2a and 2b, at the flanged portions of the pivot mounting element 2. The resilient character of the lever 3 permits the side members 3c and 3d to be resiliently spread over these extending flanged edges 2a and 2b, which lie above the side members 3c and 3d when the elements are in the closed position as shown in Fig. 5 of the draw-

ings. When closing my shoe latch for drawing the uppers 6 and 7 together, as shown in Fig. 1 of the drawings, the end 1a of the flexible tension member 1 is simply forced downwardly, and with a single downward motion thereof the lever 3, at its outswinging portion, is pivoted in connection with the end 1a of the tension member 1, and it is also pivoted at its end portions 3a and 3b within the side walls of the pivot mounting element 2. As the lever 3 progressively moves into parallel relationship with the plane of the web 2d of the pivot mounting element 2, the converging flange portions or edges 2a and 2b cause progressive spreading of the side members 3c and 3d of the lever 3 until these side members snap over the edges 2a and 2b and resiliently pass toward each other beneath the flanges 2a and 2b, which causes interfering locking relationship of the lever 3 in substantially parallel relationship with the web 2d of the pivot mounting element 2. In this condition, my shoe latch securely holds the tension member 1 in certain predetermined position for maintaining the uppers 6 and 7 properly fitted to the foot of the wearer.

When it is desired to adjust the tension member 1 at its end 1a relative to the upper 6 of the shoe, the stud 4 is released by screw-threadably rotating the nut 5, permitting the shank 4d of the stud 4 to be moved longitudinally of the slot 6a and fixed in the desired position, wherein subsequent pivotal locking of the lever 3 will cause the proper tension in the tension member 1, proportional to the desired fitted relationship of the uppers 6 and 7 over the instep of the wearer's foot. It will be here noted that the slot 5a in the nut 5 is arranged to accommodate a suitable instrument, such as a screw-driver, or preferably a coin, and this slot 5a so arranged permits a person to conveniently adjust my shoe latch in a predetermined manner to fit the foot of the wearer properly. Subsequent changes in adjustment may be readily made as desired, as hereinbefore described, and the length of the slot 6a in the shoe upper 6 provides for considerable adjustment well within the range of the variations possible for the particular size and style of shoe.

It will be noted that as the lever is swung toward the closed position, it is not necessary to steer anything to correct position for fastening or securing, nor to perform a separate fastening operation. One swing, one motion—that is all. The lever is steered automatically and precisely into its fastened position. In this, human error produces no resultant delay or difficulty.

In the modified structure, as shown in Figs. 10 to 12, inclusive, of the drawings, I have provided a nut 8, similar to the nut hereinbefore described, and this nut 8 is provided with a slot 8a similar to the slot 5a of the nut 5, except that the bottom of the slot 8a is straight from one peripheral portion of the nut 8 to the opposite portion thereof, it being noted, however, that this slot 8a extends chordally of the nut at one side of the periphery or peripheral outline of the internally screw-threaded opening 8b therein. As shown best in Figs. 11 and 12 of the drawings, the nut 8 is provided with a large diameter frictional bearing portion 8c near the periphery thereof, reduced at the middle portion of the nut, in order to cause efficient frictional engagement of said nut on the object against which it bears. In operation, the nut 8 may be screw-threaded on a suitable ex-

ternally screw-threaded nut at its internally screw-threaded bore portion 8b, and various instruments, such as screw-drivers, or other straight edged objects, may be placed in the slot 8a and extended from the axis of the bore 8b in order to provide a retention for tightening the nut 8 on its respective screw-threaded bolt or stud.

The modified structure as shown in Figs. 13 to 15, inclusive, is similar in construction to that as shown in Figs. 10 to 12, inclusive, except that a tool-engaging recess 9a is provided in the nut 9, outwardly of the periphery of the bore 9b, which is an internally screw-threaded bore portion. This tool-engaging recess 9a may be conveniently engaged by a conventional screw-driver commonly known as the "Phillips" screw-driver, which employs four radiating engaging portions at its extending end.

It will be here noted that each of the nuts 5, 8 and 9 hereinbefore described, may be used with various tools which engage the various tool-engaging recesses therein, and that these various nuts may be used in connection with various externally screw-threaded bolts wherein arcuate periphery of the nut is desirable, or in such installations of mechanism wherein the nut must be very neat and compact.

Though I have shown and described a particular construction, combination and arrangement of parts and portions, and certain modifications, I do not wish to be limited to this particular construction, combination and arrangement, nor to the modifications, but desire to include in the scope of my invention the combination, construction and arrangement, and the modifications, substantially as set forth in the appended claims.

Having thus described my invention, what I claim as new and desire to secure by Letters Patent is:

1. In a latch, the combination of: a first securing member having a substantially flat base portion, and having a pair of rails along the sides thereof, said rails being substantially parallel, each of said rails including a main portion adjacent the base portion and a bent flange extending from said main portion at the outer end thereof, and each of said main portions having a hole adjacent an end thereof, said holes being substantially aligned in a plane normal to said main portions of said rails, said flanges providing edges diverging from said main portions in a direction away from said end to provide cam faces having opposed crests; and a second securing member including a substantially U-shaped spring element having bent ends extending into said holes and journalled thereby to permit pivotal movement of said second securing member relative to said first securing member, the sides of said spring element being substantially parallel with said main portions of said rails and being adapted to slip over said crests of said cam faces and lie adjacent to said rails beneath said flanges when said securing members are in closed position, the bent ends of said spring element being movable toward and away from each other in said holes to permit said sides of said spring element to slip over said crests and spring toward said main portions of said rails when beneath said flanges.

2. In a latch adapted to connect two overlapping members, said latch including: a first securing member providing a base portion and two rails, each having an aperture adjacent an end thereof, said apertures being substantially aligned

in a plane normal to said rails, said rails extending from the sides of said base portion to provide edges diverging from each other in a direction away from said rail apertures; attachment means on said first securing member and adapted for connection to one of said overlapping members; a second securing member including first pivot means at one of its ends for pivotally connecting same to the other of said overlapping members and second pivot means at its other end for pivotally connecting same to said rails of said first securing member to permit said second securing member to swing from a plane substantially common to the plane of said first securing member through a position in which said first pivot means is opposite said second pivot means to fold toward said first securing member and assume a closed position in a plane substantially parallel to the plane of said first securing member, said second securing member including wire-like side members engaging and slipping beneath said edges of said rails as said securing members assume said closed position.

3. A latch as defined in claim 2 in which said second securing member is a wire bail having bent ends and a transverse member, said transverse member being joined to said bent ends by said wire-like side members, said transverse member comprising said first pivot means, said rail apertures receiving said bent ends to form said second pivot means, said bent ends being movable in said apertures to permit spreading of said ends, said side members engaging said diverging edges to spread said bent ends progressively as said bail moves toward closed position, said bent ends snapping toward each other when said side members pass said edges of said rails and when said securing members are in closed position.

4. A latch as defined in claim 2 in which the one of said overlapping members adapted for connection to said attachment means is slotted in the direction of overlap and said attachment means includes a projecting member extending within said slot and movable to any position along the length thereof for adjustment of said first securing member relative to said overlapping member and a securing nut threaded on said projecting member for releasably retaining said attachment means and said first securing member in any set position of adjustment.

5. A latch as defined in claim 4 in which the said nut has on its outer face an eccentrically positioned tool receiving recess adapted to facilitate manual rotation of said nut to effect retention or release of said attachment means.

6. A latch as defined in claim 4 in which the said retaining nut has on its outer face an arcuate slot adapted to receive a coin to manually turn said nut, said slot extending chordally and off center across said face of said nut.

RALPH E. JONES.
